UNITED STATES PATENT OFFICE.

WILHELM WICKE, OF CLEVELAND, OHIO, ASSIGNOR TO THE CLEVELAND SCHOOL FURNITURE COMPANY, OF SAME PLACE.

ADJUSTABLE FURNITURE.

SPECIFICATION forming part of Letters Patent No. 601,862, dated April 5, 1898.

Application filed July 27, 1896. Serial No. 600,666. (No model.)

To all whom it may concern:

Be it known that I, WILHELM WICKE, a citizen of the United States, residing at Cleveland, in the county of Cuyahoga and State of Ohio, have invented certain new and useful Improvements in Adjustable Furniture; and I do hereby declare the following to be a full, clear, and exact description of the invention, such as will enable others skilled in the art to which it appertains to make and use the same.

My invention relates to the class of adjustable school furniture in which the adjustable parts are supported upon two side standards, which are ordinarily secured to the floor.

The object of the invention is to provide novel mechanism for moving both sides of the movable portions simultaneously up or down, and also to provide mechanism for this purpose which will permit one to dispense with separate fastening devices for securing the movable parts at different elevations.

The invention consists in the construction and combination of parts hereinafter described and claimed.

In the drawings, Figure 1 is a rear elevation of a piece of furniture, including, desk, seat, and back, which embodies my invention. Fig. 2 is a sectional side elevation on line 2 2 of Fig. 1. Fig. 3 is a horizontal sectional view on line 3 3 of Fig. 2. Fig. 4 is a horizontal section on line 4 4 of Fig. 2, and Fig. 5 is a view of an alternate construction of the parts therein shown.

Referring to the parts by letters, A A represent the two side standards. Each is constructed with an upward extension a , a curved forward extension a' , and the feet a^2 , said standards being in their general form substantially like the seat-standards, which have heretofore been in common use in non-adjustable school-furniture.

The movable members of the piece of furniture, as shown, are the seat and back supports B B and the desk-supports G G. The supports for the back and seat, except that they have no legs, are shaped approximately like the standards, having the upward extensions b , to which the back H is secured, and the curved forward extensions b' , to which the seat F is pivoted. The rear edges of the

upward extension b of the supports B B lie and slide upon the front edges of the upward extensions a of the standards A A, these engaging edges being formed at any desired angle to the floor—as, for example, at right angles, as shown—depending upon the direction in which it is desired to have the supports B B move. The front edge of the part a is made V-shaped, preferably, and the angularly-disposed lugs, which project in opposite directions from the rear edge of the part b , form a guiding-groove in which said V-shaped edges of the parts a lie, whereby the sidewise movement of the supports is prevented. A curved finger a^3 , which projects forward from each part a , passes in front of a vertical rib b^3 on the part b and acts to prevent the forward movement of the part b out of engagement with the edge of part a . On the inner side of each standard is formed or secured a stud a^4 , on which is journaled a pinion C, with which is rigidly connected a bevel-gear c. In two ears $a^5 a^6$ on the inside of each standard is journaled a screw D, on the lower end of which is secured a bevel-gear d, which meshes with the bevel-gear c. An arm b^4 , which is rigid with each support B, extends between the two ears $a^5 a^6$ and the screw D screws through the end of this arm.

Adjacent to the pinions C a hole a^7 is formed in each standard A, and these holes form the bearings for a removable operating-shaft E, carrying pinions e, which engage with the pinions C. The turning of this shaft causes the revolution of the screws, whereby both supports are simultaneously moved up or down. It is unnecessary to employ any fastening devices to hold the supports in any position, because a force tending to move the said supports up or down can never be great enough to cause the revolution of the screw, without which the supports cannot move.

Some criticism may be made to the construction shown for the reason that the weight of the supports and all that they carry is borne directly by the bevel-gears c and the stud a^4 . I have found by actual experiment that this construction is strong enough for the purpose, and it has the advantage of making it more difficult to turn the screw D. As

an alternative construction the screw D may be formed with an annular flange d' , which rests upon the ear a^5 , as shown in Fig. 5.

The desk-supports G are moved up or down by like mechanism. The vertical members g of said desk-supports lie just inside and in contact with the parts a of the standards. The desk-supports are guided by an ear a^8 , secured to the part a and projecting through a vertical slot g' in the part g , and also by ribs g^2 on the desk-support, which projects into vertical grooves a^{10} in part a . The ear a^8 and another ear a^9 on each standard furnish bearings for a screw J, which screws through the arm g^4 of the desk-support and has a bevel-gear j secured to its lower end. Each screw screws through an arm g^4 on the desk-supports.

On a stud a^{11} on the inside of each standard is journaled the pinion K, having rigidly secured to it the bevel-gear k , which meshes with the bevel-gear j . Holes a^{12} , adjacent to said pinions, serve as bearings for the same operating-shaft E, whereby the pinions K, and consequently the screws J, are revolved with the result of moving the desk-supports up or down.

The shaft E, which may be removably mounted in the holes a^7 or a^{12} , is provided with pinions e for engagement with either the pinions C or K. Preferably these pinions e are formed by corrugating the shaft from end to end, as shown.

I hereby disclaim the combination, with the end frames made in separate sections and provided with cleats adapted to secure them one to the other in vertically-adjustable positions, of adjusting-screws for each of the end frames and an operating device for simultaneously operating the adjusting-screws, as I am not the first inventor of said combination of parts.

Having described my invention, I claim—

1. In adjustable furniture, the combination of two standards having each a hole for the

reception of an operating-shaft, an operating-screw journaled on the inner side of each standard, a bevel-gear secured to each of said screws, and a rigidly-connected pinion and beveled gear mounted upon the inner side of each standard adjacent to said holes therein, with the movable members which slide upon said standards, an arm rigid with each of said members with which said screws engage, and an operating-shaft adapted to be removably mounted in said holes and having pinions which engage with the pinions hereinbefore named, substantially as and for the purpose specified.

2. In adjustable furniture, the combination of two standards, each having on its inner side two ears $a^8 a^9$, a rigidly-connected pinion and beveled gear mounted on the inner side of each standard, said standards having each a hole for the reception of an operating-shaft, with two desk-supports which slide respectively against the inner sides of said standards, and have each a slot through which the ear a^8 projects, an inwardly-projecting arm, and a screw engaging with said arm, and mounted in the two ears $a^8 a^9$, and a bevel-gear secured to said screw, substantially as and for the purpose specified.

3. In adjustable furniture, the combination of two standards, each having on its inner side two ears $a^8 a^9$, and a vertical groove a^{10} , and an operating-screw mounted in said ears, with two desk-supports each having a vertical slot through which the ear a^8 projects, and a rib g^2 which projects into the vertical groove a^{10} , arms on said supports with which said screws engage, and mechanism for turning said screws, simultaneously, substantially as and for the purpose specified.

In testimony whereof I affix my signature in presence of two witnesses.

WILHELM WICKE.
